US00D984477S

(12) **United States Design Patent** (10) **Patent No.:** **US D984,477 S**
Chen et al. (45) **Date of Patent:** **** Apr. 25, 2023**

(54) **DISPLAY SCREEN OR PORTION THEREOF WITH GRAPHICAL USER INTERFACE**

(71) Applicant: **Apple Inc.**, Cupertino, CA (US)

(72) Inventors: **Kevin Will Chen**, Cupertino, CA (US); **Teofila Connor**, San Francisco, CA (US); **Lynnette Lucille Galloway**, Emeryville, CA (US); **Aurelio Guzmán**, San Jose, CA (US); **Andre Ricardo Jointe**, San Jose, CA (US); **Michael Tettey Nartey**, San Jose, CA (US); **Oladapo Onikuyide**, San Francisco, CA (US); **Shedrick Wallace Turner, Jr.**, Lithonia, GA (US)

(73) Assignee: **Apple Inc.**, Cupertino, CA (US)

(**) Term: **15 Years**

(21) Appl. No.: **29/767,931**

(22) Filed: **Jan. 26, 2021**

(51) **LOC (14) Cl.** **14-04**

(52) **U.S. Cl.**

USPC **D14/490**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is a second embodiment thereof; FIG. 3 is a third embodiment thereof; and, FIG. 4 is a fourth embodiment thereof.

The broken lines in the figures show a display screen or portion thereof, and form no part of the claimed design.
